UNITED STATES PATENT OFFICE.

CLIFFORD G. CROOK, OF PITTSBURGH, PENNSYLVANIA.

MACHINE FOR PACKING GOODS.

1,363,395.

Specification of Letters Patent. Patented Dec. 28, 1920.

Application filed August 15, 1919. Serial No. 317,712.

To all whom it may concern:

Be it known that I, CLIFFORD G. CROOK, a citizen of the United States, and a resident of Pittsburgh, in the county of Allegheny and State of Pennsylvania, have invented a new and useful Improvement in Machines for Packing Goods; and I do hereby declare the following to be a full, clear, and exact description thereof.

10 My invention relates to a machine for packing goods, and has special reference to the packing of goods, such as candies in boxes, wherein goods of the same kind and shape, or goods of different kinds and shapes are packed in boxes for shipment or for sale.

Heretofore, in the packing of goods, such as candies, and particularly when it is desired to pack a large number of boxes at 20 one time, the empty boxes are laid upon a table against each other, and then each of the packers has a large box or receptacle in his hands or in his arms or on his arms, with each containing different candies to be 25 placed in such empty boxes. In this case, the packers are required to walk around such table while picking out the candies from their boxes or receptacles, so that they can place the required amount or number in each 30 of the empty boxes, and thus a great deal of time was consumed in this process due to the packers' interference with each other. It was also very laborious for the packers on account of the walking and carrying 35 which was necessary.

The object of my invention is to overcome these objections and difficulties by providing a cheap, simple and efficient machine for packing these goods, which will do away 40 with carrying of the goods to be packed, will overcome the walking required, and will enable the goods to be packed in a much faster time.

A still further object of the invention is 45 to provide such a machine on which the trays for carrying the different goods or candies to be packed will be capable of having different and intermittent speeds for the purpose of packing boxes of different sizes or 50 quantities.

To these ends my invention consists, generally stated, in the novel machine for packing goods, as hereinafter more specifically set forth and described and particularly 55 pointed out in the claims.

To enable others skilled in the art to

which my invention appertains to construct and use my improved machine for packing goods, I will describe the same more fully, referring to the accompanying drawings, in 60 which:

Figure 1 is a side elevation of my improved machine for packing goods;

Fig. 2 is a sectional plan or top view of the same, taken on the line 2—2 Fig. 1, looking 65 in the direction of the arrows;

Fig. 3 is an end view of the machine, taken on the line 3—3 Fig. 1, looking in the direction of the arrows;

Fig. 4 is a cross-section of the machine, on 70 the line 4—4 Fig. 1 looking in the direction of the arrows;

Fig. 5 is a sectional view showing one of the power driven sprocket wheels employed and its operating lever, and taken on the 75 line 5—5 Fig. 3;

Fig. 6 is a view showing a portion of the gearing mechanism;

Fig. 7 is a section of the gearing mechanism on the line 7—7 Fig. 3, looking in the 80 direction of the arrows;

Fig. 8 is a view of the tray hanger;

Fig. 9 is an enlarged sectional view of the trays and carrying chain for same; and

Fig. 10 is an elevation of one of the trays. 85

Like symbols of reference indicate like parts in each of the figures of the drawings.

As illustrated in the drawings, my improved machine is shown at A, and is formed from and supported by suitable 90 frame work 1 built up from the floor a. Within the frame 1 and on each side of the machine is a separate chain 2, which passes over sprocket wheels 3, 4 at each end of the machine and mounted on the shafts 5 and 95 6. The shaft 5 is mounted in suitable adjustable bearings 5' at the front end of the machine A and the shaft 6 is mounted in suitable bearings 6' at the rear end of the machine. Extending across between the 100 chains 2 are the receiving trays 7, which are pivotally connected to said chains through the hangers 8, such pivots being indicated at 9, and being at the upper ends of such hangers in order that the trays will have a 105 swinging or tilting motion, but will always remain in a horizontal position for receiving and carrying the goods to be packed in the movement of the chains. The trays 7 will also be removable from the hangers 8 110 by reason of the plates 7' forming the supporting bases or bottoms of the trays being

separable and resting upon the removable flange portions 8' placed on ledges 8" on said hangers, and upwardly extending flanges 7" are also formed on said portions 5 to hold the goods to be packed on said trays, such portions and plates being held by said ledges resting on the same, with the portions resting in a seat 9' in said ledges.

Mounted upon the floor a is a suitable 10 motor 10 which has a small pulley 11 mounted upon the main shaft 12 of the same and around which pulley and a larger pulley 13 mounted on the cross-shaft 14 a belt 15 passes. A small sprocket wheel 16 is also 15 mounted on the shaft 14 and around such wheel and a larger sprocket wheel 16' on the cross shaft 17 a chain 18 passes. A sprocket wheel 19 is also mounted on the shaft 17 and around which and a larger sprocket 20 wheel 20 on the cross-shaft 21 a chain 21' passes, which shaft 21 has suitable gearing mechanism B connected therewith, as hereinafter described.

Above the trays 7 and supported by the 25 frame-work 1 is the storage bin or receptacle 22 for the empty boxes to be filled, which is provided with inwardly tapered open sides 23, formed of strips of wire cloth, and an opening 24 below each of the same, so that 30 such boxes will be directed to such openings and against the bottom 22' of said bin to enable them to be withdrawn through the openings when desired, as hereinafter described.

35 Extending along each side of the frame work 1 and exteriorly of the machine A is a bench 25, and under each of the same is a conveyer belt 26, which passes over a pulley 27 at the front end of the machine and 40 over a pulley 28 in a wrapping table 29, at the rear end of the machine. A supporting shelf 30 extends out from the frame-work 1 under the upper portion of the belt 26 to hold the same level and permit it to slide 45 along the same, and a guard 30' extends out from such frame under the lower portion of such belt to keep the same from sagging down and interfering with the operatives.

Mounted on the shaft 6 is the sprocket- 50 wheel 31 around which passes a sprocket-chain 32, which also passes around a sprocket wheel 33 mounted on a shaft 34 carrying the pulley 28, while an idler 35 mounted under the table 29 engages with 55 the bottom portion of the belt 26 to hold the same taut in passing over the pulleys 27 and 28, and such belt through these connections is adapted to run at a slower rate of speed than the trays 7.

60 The gearing mechanism B is connected up with the shaft 21 and mounted upon one side of the machine A, and upon said shaft 21 adjacent the sprocket wheel 20 is the sprocket wheel 36, and such wheels are of 65 the same diameter. A chain 37 passes

around the sprocket wheel 36 and over a sprocket wheel 38 mounted upon the shaft 17, and such wheel is smaller in diameter than the wheel 36. A clutch 39 is mounted on the shaft 21 between such wheels 20 and 70 36 for engagement with the same when desired, and a yoke lever 40 is connected to such clutch for operating the same.

Mounted upon the shaft 21 on the opposite side of the machine A from the wheels 75 20 and 36 is a gear wheel 41, which meshes with a larger gear wheel 42 mounted on a shaft 43 above and in line with the shaft 21, and mounted on said shaft 43 are the two gear wheels 44 and 45, which are of the 80 same diameter, except that the wheel 44 is provided with only a toothed section 45' thereon for engagement with the gear wheel 46 when desired. This wheel 46 is movably mounted on a shaft 47 which is above and 85 in line with the shaft 43 and such wheel is adapted to be moved along said shaft 47 by means of a yoked lever 48 engaging with a hub 49 on one side of the same. A gear wheel 50 is also mounted upon the shaft 47 90 and meshes with a smaller gear wheel 50' mounted upon the shaft 6 which is also above and in line with said shaft 47.

The use and operation of my improved machine for packing goods is as follows: 95

When the machine A is placed in operation in any suitable manner by any suitable means, such as the motor 10, acting through the shafts 12, 14, 17, 21, 43, 47 and 6 will 100 through the interposed connections between the same, as previously described, operate, so that the conveyer formed by the chains 2 and trays 7, as well as the belt 26 will travel in the direction of the arrows, shown in Fig. 2. The trays 7 being provided with the 105 goods to be packed and the storage bin 22 provided with the empty boxes desired, such boxes can be packed in the following manner.

In the case of mixed or assorted candies, 110 boxes or receptacles containing the same are placed upon the trays 7, with two of the same kind upon each tray, as described, and the girls or other operatives are seated along 115 each of the benches 25, so that as each operator pulls out an empty box from the bin 22 through the openings 24 and by holding the same in one hand or by placing the same on the bench 25, they can with the other hand pick the amount of candy desired from 120 the receptacles passing along in the trays 7 in front of such operators. When the operatives have filled the boxes, they are then placed on the belts 26 which carry the same back into the table 29 where they are 125 removed from the belts by the operatives seated around such table and the lids placed on the same, after which they can be weighed by the operators around the table 29, and wrapped in the usual manner.

In case it is desired to change the speed of the moving trays 7, such as for instance, when larger boxes are to be packed, the clutch 39 is so operated by the lever 40 to engage with the sprocket wheel 20 and such wheel being connected by chain 21 and with the sprocket wheel 19 on the shaft 17, as previously described, the shaft 21 is operated at a slower speed than when the sprocket- 10 wheel was engaged by said clutch owing to the differences in sizes of the wheels 19 and 36. This slower movement of the shaft 21 will operate the shaft 6 through the gearing B at a slower speed and allows the operatives more time when packing larger boxes. 15

When it is desired to pass still larger boxes and where several pieces are to be taken from the same receptacle on the trays 7 or from the said trays, an intermittent 20 drive is provided by the shifting of the gear 46 into engagement with the gear 44, at which time such gear 46 will be operated intermittently by reason of the toothed portion or segment 45' on said gear 44 and such 25 trays will move forwardly along and then stop in front of the operatives for a predetermined period, so that the operatives may have sufficient time to extract as many pieces as desired from such trays in the packing of 30 said larger boxes.

It will thus be seen that by reason of the change in speeds of shaft 21 and the continuous and intermittent gearing between shafts 43 and 47 in such gearing B, variations 35 of speeds, either continuous or intermittent, may be obtained.

It will also be seen that my improved method and machine for packing goods will enable the operatives to sit easily and comfortably 40 around the machine and pack the goods quickly and easily, and thus overcome the laborious and irksome task of walking around a table carrying the goods to be packed.

It will further be seen that the goods to be packed will be within easy reach of the operatives at all times and the empty boxes for packing will also be within reach, so that a continuous and steady packing of the 50 goods can be kept up and maintained during the operation of packing and wrapping the goods.

It will also be obvious that the operatives will be enabled to work faster and steadier 55 without interference with each other in the packing of goods, and by reason of the arrangement of the device the operators are enabled to pack the goods from each of the trays in passing and each of the packed 60 goods will be carried away from the machine for weighing and wrapping. This arrangement of the device will also permit the trays to travel through the machine continuously and in a horizontal position at all times, 65 and they will not be liable to spill, drop or

empty the goods to be packed which are carried by them.

It will be understood that my improved machine for packing goods may be used for the packing of goods other than candies or 70 other like goods, and when used in connection with such goods, candies of different kind and shape and of the same shape and kind can be packed, either by being individually packed in the boxes from the trays 75 or in batches.

Various modifications and changes in the design and construction of my improved machine may be resorted to without departing from the spirit of the invention or sacrificing any of its advantages. 80

What I claim as my invention and desire to secure by Letters Patent is:

1. In a candy packing machine, in combination, an endless conveyer, a plurality of 85 trays for receiving goods to be packed, said trays being pivoted to said conveyer, so as to remain horizontal at all times, a work bench for supporting the boxes to be packed during the packing operation, said work 90 bench being disposed in a position such as to permit easy access both to it and to said trays, an endless conveyer for receiving the packed boxes, said last named conveyer being disposed in a position permitting convenient 95 access to it and to said bench and said first-named conveyer, means for driving the conveyers, and means for enabling said tray carrying conveyer to be moved intermittently or continuously at varying 100 speeds.

2. In a candy packing machine, in combination, an endless conveyer, a plurality of trays for receiving goods to be packed, said trays being pivoted to said conveyer, so as 105 to remain horizontal at all times, a work bench for supporting the boxes to be packed during the packing operation, said work bench being disposed in a position such as to permit easy access both to it and to said 110 trays, an endless conveyer for receiving the packed boxes, said last named conveyer being disposed in a position permitting convenient access to it and to said first-named conveyer, power-operated means for driving 115 the conveyers, and gearing means for enabling said tray carrying conveyer to be moved intermittently or continuously at varying speeds.

3. In a candy packing machine, in combination, an endless conveyer, a plurality of trays for receiving goods to be packed, said trays being pivoted to said conveyer, so as to remain horizontal at all times, a work bench for supporting the boxes to be packed 120 during the packing operation, said work bench being disposed in a position such as to permit easy access both to it and to said trays, an endless conveyer for receiving the packed boxes, said last-named conveyer be- 125 130

ing disposed beneath the work bench in a position permitting convenient access to it and to said bench and said first-named conveyer, and power operated means for enabling said tray carrying conveyer to be moved continuously or intermittently at different speeds.

4. In a candy packing machine, in combination, an endless conveyer, a plurality of trays for receiving goods to be packed, said trays being pivoted to said conveyer, so as to remain horizontal at all times, a work bench for supporting the boxes to be packed during the packing operation, said work bench being disposed in a position such as to permit easy access both to it and to said trays, and an endless conveyer for receiving the packed boxes, said last-named conveyer being disposed in a position beneath the work bench and permitting convenient access to it and to said bench and said first-named conveyer.

5. In a candy packing machine, in combination, an endless conveyer, a plurality of trays for receiving goods to be packed, said trays being pivoted to said conveyer, so as to remain horizontal at all times, a work bench for supporting the boxes to be packed during the packing operation, said work bench being disposed in a position such as to permit easy access both to it and to said trays, an endless conveyer for receiving the packed boxes, said last-named conveyer being disposed in a position permitting convenient access to it and to said bench and said first-named conveyer, and a receptacle for receiving empty boxes, said receptacle extending substantially throughout the length of said first-named conveyer and being disposed so as to permit of easy access to it and to said conveyers and bench.

6. In a candy packing machine, in combination, an endless conveyer, a plurality of trays for receiving the goods to be packed, said trays being pivoted to said conveyer so as to remain horizontal at all times, a receptacle for empty boxes, said receptacle being disposed immediately above said conveyer and extending substantially throughout the length of the latter, a pair of benches, one at each side of said conveyer, for supporting the boxes during the packing operation, said benches extending substantially throughout the length of the conveyer, and a pair of endless conveyers for receiving the filled boxes, said last-named conveyers being disposed one adjacent to and beneath each of the said benches, for the purposes set forth.

7. A candy packing machine comprising a frame, a conveyer in said frame for carrying supplies of candy to be packed, a work bench extending outwardly from the frame and closely adjacent the supply car-

rying conveyer, and conveying means immediately beneath said bench for removing the packed boxes.

8. A candy packing machine comprising a frame, a conveyer in said frame for carrying supplies of candy to be packed, a work bench extending outwardly from the frame and closely adjacent the supply carrying conveyer, conveying means beneath said bench for removing packed boxes, and a receptacle for containing the boxes to be filled supported in said frame above the supply carrying conveyer.

9. A candy packing machine comprising a frame, a conveyer in said frame for carrying supplies of candy to be packed, a work bench extending outwardly from said frame and adjacent the supply conveyer, means adjacent the work bench for conveying packed boxes away, means for driving said supply carrying conveyer, and means in the driving connection whereby the supply carrying conveyer may be moved intermittently or continuously at varying speeds.

10. A candy packing machine comprising a frame, a conveyer in said frame for carrying supplies of candy to be packed, a work bench extending outwardly from said frame and adjacent the supply conveyer, an endless conveyer adjacent the work bench for conveying packed boxes away, a common means for driving both of said conveyers, and means whereby the candy supply carrying conveyer may be moved intermittently or continuously at varying speeds and for correspondingly varying the speeds of the box carrying conveyers.

11. A candy packing machine comprising a frame, a longitudinally extending conveyer supported in the frame, a work bench extending outwardly from each side of the frame adjacent the conveyer and substantially coextensive therewith, and conveying means beneath said benches for removing packed boxes.

12. A candy packing machine comprising a frame, a longitudinally extending conveyer supported in the frame, a work bench extending outwardly from each side of the frame adjacent the conveyer and substantially coextensive therewith, conveying means beneath said benches for removing packed boxes, and a hopper above the supply carrying conveyer and extending throughout the greater portion of its length, said hopper permitting boxes to be removed therefrom at either side throughout substantially its entire length.

In testimony whereof, I, the said CLIFFORD G. CROOK, have hereunto set my hand.
CLIFFORD G. CROOK.
